UNITED STATES PATENT OFFICE.

CLARENCE B. FOWLER, OF QUEENS, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed August 12, 1925. Serial No. 49,741.

This invention relates to telephone systems and particularly to systems for interconnecting rural or magneto lines with common battery lines.

5 An object of this invention is to provide improved rural subscribers' or magneto lines suitable for interconnection with common battery lines through cord circuits that are ordinarily used for interconnecting common 10 battery lines only.

A feature of this invention resides in the provision of means for supervising connections over magneto lines. Other features of the invention are the provision of means 15 for intermittently displaying a signal at the central office terminal of a magneto line when a subscriber on said line is calling by actuating his generator; for displaying a steady signal after the subscriber on this line 20 has ceased to operate his generator; for intermittently displaying the signal when the subscriber reoperates his generator either as a recall signal or a disconnect signal; and for extinguishing the signal when an operator 25 at the central office makes connection with the subscriber's line.

Other features not specifically mentioned will appear from the following description, taken in conjunction with the accompanying 30 drawings, in which Fig. 1 shows a complete circuit arrangement required for a connection through a universal cord circuit between a common battery and a magneto line, the latter of which embodies the features of this 35 invention, while Fig. 2 shows a modified form of a portion of the magneto line embodying this invention.

Referring to Fig. 1, A represents a common battery subscriber's station, B represents a rural subscriber's station, M represents the magneto line circuit arranged in accordance with this invention and associated with station B, while C represents a universal cord circuit adapted for inter- 45 connecting stations A and B. Considering the operation of this system on a connection from station B to station A, a call will be initiated by the subscriber at station B actuating ringing generator 10 to produce an alternating current on the line. An alternating current responsive relay 11 will now become energized in an obvious circuit through the generator 10. The energization of relay 11 causes relay 12 to operate 50 in an obvious circuit through the right hand

armature and front contact of relay 11. The operation of relays 11 and 12 causes the operation of relay 13 in a circuit from battery, left hand winding of relay 13, armature and front contact of relay 12 to ground 60 through the right hand armature and front contact of relay 11. Relays 12 and 13 are now located up to the ground at the inner right hand armature and front contact of relay 13.

It should be noted that with relays 11 and 13 operated, that is, during the period that the generator 10 is being operated, lamp 14 will be intermittently lighted and extinguished. The original energizing circuit for the lighting of lamp 14 may be traced from battery, lamp 14, resistance 16, outer right hand armature and front contact of relay 13 to ground. A short circuit for lamp 14 will be alternately provided through the interrupter 15 as follows: battery, interrupter 15, left hand armature and front contact of relay 11, middle right hand armature and front contact of relay 13, resistance 70 17, resistance 16, outer left hand armature 80 and front contact of relay 13 to ground, that is, lamp 14 will therefore alternately be lighted or extinguished as long as the generator 10 is operated.

The operator at the central office wherein 85 cord C is located, noting the intermittent flashing of lamp 14 will interpret the signal as a calling signal from the subscriber at station B and answer it by inserting plug 18 into jack 19. This connection of the plug and jack will close a circuit for relays 20 and 21 from battery, both windings of relay 21 in series, sleeve terminals of the plug and jack, left hand armature and front contact of relay 13, middle winding of relay 90 20 to ground. Relay 21 will operate in this circuit whereas relay 20 will not operate at this time due to the high resistance of the left hand winding of relay 21.

The operator now actuates her listening 100 key 29 to ascertain the number wanted by the subscriber at station B and in so doing shunts the left hand winding of relay 21 to battery associated with the lower closed contacts of key 29, and relay 20 will therefore 105 operate due to the lowered resistance in the sleeve circuit. As relay 20 becomes energized it provides a circuit from ground, inner right hand armature, front contact and right hand winding of relay 13, right hand 110

armature and front contact and right hand winding of relay 20 to battery, and relay 13 being of the differential type will thereby release. The release of relay 13 opens the circuit for relay 12 which will also release. The release of relay 13 opens the circuits for lamp 14 through its outer and middle right hand armatures and front contacts so that the lamp 14 will now be extinguished. The release of relay 13 opens the circuit for relay 20 at its left hand armature and front contact but closes the sleeve circuit instead through its make-before-break contact through a resistance to ground so that relay 21 will not release.

On the connection of the plug 18 into jack 19 relay 23 becomes operated through a circuit from battery, lower right hand winding of repeating coil 24, winding of relay 25, ring terminals of the plug and jack, winding of relay 23, retardation coil 38, tip terminals of the jack and plug, upper right hand winding of repeating coil 24 to ground. Relay 23 in energizing closes an obvious circuit for relay 27 which relay in operating opens the full metallic circuit for the line to the subscriber at station B. The opening of this circuit is for the purpose of supplying a condenser circuit during conversation between the operator and the subscriber's station B. As relay 25 is included in the circuit with relay 23, it operates immediately upon the insertion of plug 18 into jack 19 and thereby prevents the operation of lamp 28 on the operation of relay 21.

The operator now ascertains the number of the wanted subscriber and proceeds to extend the connection to the subscriber at station A by inserting plug 30 into jack 31. As is well known in the art, relay 32 operates through the sleeve circuit closing a circuit for lamp 33 which lights as a supervisory signal. The operator now operates her ringing key 26 and applies ringing current from the source 35 and ground 36 as is well known in the art. This operation calls the wanted subscriber at station A and when this subscriber answers the call, relay 34 operates and extinguishes lamp 33. As is evident from examination of the drawing the connection will now be completed between the stations A and B and the subscribers at these stations may begin conversation.

In case the subscriber at station B desires to recall the operator during this connection or to transmit a ring-off signal that the conversation is concluded, he operates generator 10. Relay 11 will then again be operated causing the relays 12 and 13 to be operated and the lamp 14 alternately lighted and extinguished as hereinbefore described. As the operator does not know whether the subscriber at station B is ringing off or desires to recall her, she will now operate her listening key 29 and thereby connect her opera-

tor's set to the line. The operation of key 29 causes relay 20 to operate as hereinbefore explained and this relay will in turn cause relays 12 and 13 to release provided, of course, that the subscriber has ceased ringing. Relay 13 in releasing causes the sleeve circuit to be transferred from the ground through the winding of relay 20 to ground through a resistance at the make-before-break contacts, so that relay 20 will now be released as hereinbefore described. The operator will now ascertain whether the calling subscriber has disconnected or whether he desires to make another call. If the calling subscriber has disconnected, the operator will remove plug 18 from jack 19 causing relays 25, 21, 23 and 27 to release and the circuits are restored to normal. If another connection is desired by the subscriber at station B, the operator at C restores her listening key 29 to normal and attends to the second call, which is now handled in the same manner as the first call as hereinbefore described.

Considering now the extension of a call in the opposite direction, that is, from the common battery station A to magneto station B, the operator will insert answering plug 18 into jack 31 on the reception of the usual indication from the subscriber at station A that the connection is desired. On the insertion of this plug, relay 21 will be operated but lamp 28 will remain unoperated as relay 25 will operate the moment the connection between the plug and jack is made. The cutoff relay of the calling line operates in series with both windings of relay 21 so that the line lamp is extinguished immediately and irrespective of whether the operator has operated her listening key 29. The operator now operates her listening key 29 and ascertaining the number of the wanted subscriber then inserts the calling plug 30 into jack 19 of the line of the subscriber at station B. As plug 30 is inserted in jack 19 relays 34, 23, 27 will be operated and the operation of relay 27 opens the metallic circuit to the subscriber's station and substitutes therefor a condenser circuit for talking purposes as hereinbefore described while the operation of relay 34 prevents the lighting of lamp 33 on the obvious operation of relay 32 over the sleeve circuit.

In order to call station B the operator now actuates ringing key 26 and thereby causes the release of relays 34, 23 and 27 so that the metallic circuit from the key 26 to the subscriber's line is again complete. A circuit is thereupon closed as follows: from the source of ringing current 35, lower inner contacts of ringing key 26, ringing terminals of the plug 30 and jack 18, ring conductor of line M through the lower armature and back contact of relay 27, the subscriber's loop, tip conductor of line M through the

upper armature and back contact of relay 27, tip terminals of the jack and plug, upper alternate contacts of the ringing key 26 to ground. As it is necessary that some means for closing the metallic circuit to the subscriber's station be provided for ringing purposes, relay 23 operates only on direct current and therefore releases on the operation of key 26 and does not operate on the application of ringing current to the line. When the ringing key is restored to normal, relays 23 and 27 will again operate whereupon a metallic circuit will be opened and the condenser circuit, as shown, substituted, over which the two interconnected subscribers may carry on a conversation. When the subscriber at station B answers this call by lifting his receiver off the hook, the operator will release her keys and conversation between the two subscribers may take place.

On the restoration of the receiver hook by the subscriber B at the end of the conversation and on the usual ring-off signal, the operator will test the wanted subscriber's line as hereinbefore described and restore the line to normal by removing plug 30 from jack 19 if the subscriber at station B does not desire to secure another connection. When the common battery subscriber at station A replaces his receiver, relay 25 will be deenergized whereupon lamp 28 will become lighted in an obvious circuit to ground through the armature and front contact of relay 25. The operator will now remove plug 18 from jack 31 and relay 21 and lamp 28 will be restored to a normal condition.

It will be noted therefore that by the means outlined as above, the subscribers equipped with different types of lines may easily and expeditiously be associated with each other and that in accordance with this invention means for properly supervising such connections is provided.

Referring now to Fig. 2 of the drawings, if the leads *a*, *b*, and *c* are connected at the line X of Fig. 1 in place of the equipment shown below this line, a modified form of the invention may be provided.

In this case, if, for example, a connection is desired from the subscriber's station B, relay 11' will become operated causing relay 12' to operate in an obvious circuit. The operation of relay 12' closes an obvious circuit for lamp 14' from ground through the interrupter 15' and the lamp 14' will therefore be alternately lighted and extinguished as this circuit is alternately completed or opened through the interrupter 15'. The operation of relay 12' also closes the following circuit for relay 41: battery, armature and back contact of relay 20', winding of relay 41, inner right hand armature and front contact of relay 12' to ground. Relay 41 will close a locking circuit for itself to ground, through its outer right hand armature and front contact. It will therefore be seen that as long as the generator 10 is operated lamp 14' will be alternately operated and extinguished to indicate to the operator at C that a connection is desired.

If the subscriber at station B ceases ringing lamp 14' will be steadily lighted by the release of relays 11' and 12'. This circuit for maintaining lamp 14' steadily lighted, may be traced as follows: battery, lamp 14', left hand armature and back contact of relay 12', inner right hand armature and front contact of relay 41 to ground. When the operator at C answers this call, relay 20' will be operated in the same manner as was relay 20 in Fig. 1. On the operation of relay 20' the circuit for relay 41 will be opened at the armature and back contact of this relay and consequently lamp 14' will be extinguished.

If the subscriber at station B desires to recall the operator at C or give the usual ring-off signal he may operate his generator 10 as hereinbefore described causing the operation of relays 11' and 12' in succession. On the operation of relay 12' lamp 14' will be alternately lighted and extinguished by the interrupter 15' thereby calling the attention of the operator to this connection. As relay 20' is now operated relay 40 will become operated over a circuit as follows: battery, armature and front contact of relay 20', winding of relay 40, outer right hand armature and front contact of relay 12' to ground. Relay 40 will close a locking circuit for itself through its outer right hand armature and front contact to ground so that when the subscriber at station B ceases ringing, the lamp 14' will be steadily lighted. This circuit may be traced as follows: battery, lamp 14', left hand armature and back contact of relay 12', inner right hand armature and front contact of relay 40 to ground. If this signal from the subscriber at station A is a ring-off signal, the operator at C simply removes plug 18 from jack 19 thereby releasing relays 20' and 40 and extinguishing lamp 14'. If another connection is desired by the subscriber at station B, the operator at C removes plug 18 from jack 19 and either inserts the answering plug 30 of the same cord or the answering plug of any other cord circuit that she may find more convenient to employ for completing this second connection. The insertion of this second plug into jack 19 the second time will cause it to function in the same manner as hereinbefore described.

What is claimed is:

1. In a telephone system, a telephone line having a subscriber's station at one end thereof and central office switching equipment at the other end thereof, a generator at the said station, a line lamp at the said central office end of said line, and means

under control of said generator for causing said line lamp to flash during the operation of said generator and to light steadily after the operation of said generator.

- 5 2. In a telephone system, a telephone line having a subscriber's station at one end thereof and central office switching equipment at the other end thereof, a generator at the said station, a calling signal at the 10 said central office end of said line, a cord circuit for connection with said line having means to control said signal, and means under control of said generator for causing said signal to operate intermittently during 15 the operation of said generator and to operate steadily after the operation of said generator, said means being effective both before and after said cord circuit is connected to said line.
- 20 3. In a telephone system, a telephone line having a subscriber's station at one end thereof and central office switching equipment at the other end thereof, a generator at the said station, a calling signal at the 25 said central office end of said line, means under control of said generator for causing said signal to operate intermittently during the operation of said generator and to operate steadily after the operation of said 30 generator, a cord circuit for connection with said line having means to control said signal, means responsive to the connection of said cord circuit to said line and under control of said generator for causing said signal 35 to operate intermittently during the operation of said generator and to operate steadily after the operation of said generator.
4. In a telephone system, a common battery subscriber's station, a magneto subscriber's station, including a generator, an operator's position and a link circuit thereat, a line circuit for extending said magneto subscriber's station to said operator's position, a signal associated with said line circuit,

circuit, a pair of condensers associated with 45 said line circuit, said link circuit being adapted to interconnect said common battery subscriber's station and said line circuit, means in said line circuit operated in response to the actuation of said generator 50 for causing said signal to operate in a characteristic manner, manually operable means in said link circuit, means responsive to the connection of said link circuit and said line circuit and to the operation of said manual 55 means for restoring said signal and for including said pair of condensers in said line circuit to form a talking path between said subscribers' stations.

5. In a telephone system, a magneto subscriber's station and a line circuit therefor, a common battery subscriber's station, a link circuit for interconnecting said stations, a signal in said line circuit, an electromagnetic means in said line circuit having a plurality of windings, an electromagnetic means in said link circuit having a plurality of windings, a manually operable means in said link circuit, subscriber controlled means at said magneto station for causing the operation of said signal in a characteristic manner, means responsive to the connection of said link circuit and said line circuit for associating one of said windings of said electromagnetic device in said line circuit 65 with all of said windings of the electromagnetic device in said link circuit and means responsive to the actuation of said manually operable means for causing the disassociation of one of the windings of the electromagnetic device in said link circuit from the electromagnetic device in said line circuit whereby said signal is restored and said electromagnetic device in the line circuit caused to deenergize.

In witness whereof, I hereunto subscribe my name this 7th day of August A. D., 1925.

CLARENCE B. FOWLER.
